UNITED STATES PATENT OFFICE.

JOHN ANDERSON RUFFIN, OF NEW YORK, N. Y., ASSIGNOR TO THE
HAMMOND TYPEWRITER COMPANY, OF NEW YORK, N. Y.

TYPE-WRITER ATTACHMENT.

No. 836,148.

Specification of Letters Patent.

Patented Nov. 20, 1906.

Application filed December 30, 1904. Serial No. 238,968.

To all whom it may concern:

Be it known that I, JOHN ANDERSON RUFFIN, a citizen of the United States, residing at New York, N. Y., have invented certain new and useful Improvements in Type-Writer Attachments, of which the following is a specification.

My invention is an attachment for typewriters, and particularly for that class of machines known as the "Hammond."

The attachment is designed to adapt the machine for printing tags—for instance, such as are used in railroad-offices for checking up the cars of the road. The tags are arranged in rolls united together, and one of these rolls is received by the attachment and is fed to the printing mechanism, and after the printing has been placed upon the tag the said tag is severed from the strip composing the roll and is deposited in a suitable receptacle for use in checking up the cars.

My attachment includes means for holding and feeding the strip of tags, so that the printing may be placed thereon, and means for severing automatically the printed tag from the strip.

The invention includes, further, the features and combination and arrangement of parts hereinafter described, and particularly pointed out in the claims.

In the accompanying drawings, Figure 1 is a side view of so much of the Hammond type-writer as is necessary to a clear understanding of my invention, which is shown as attached thereto. Fig. 2 is a plan view of a Hammond type-writer with parts in section and some of the parts omitted. Fig. 3 is a rear view of the machine with the attachment applied. Fig. 4 is a side elevation of the attachment looking from the left of Fig. 3. Fig. 5 is a detail view of feed mechanism associated with the attachment. Fig. 6 is a detail view of the detent ratchet-wheel and its detent for holding the feed-rolls against backward movement or overthrow when moved by their operating mechanism.

My improvements relate more particularly to the carriage and feed mechanism of the type-writer; and my objects are to provide an attachment that may be fitted to the ordinary carriage and feed mechanism of the type-writer and to provide an attachment that may be fitted to the ordinary carriage now in use of the Hammond type-writer, though if the machine is built especially for the printing of tags the carriage may be altered in certain minor particulars from the ordinary form, as will be noted hereinafter.

In the drawings, 1 indicates the type-writer carriage, which is of substantially the ordinary form. This carriage has end frames 2, with a rack-bar 3 extending between them, and also an upper bar or plate 4. Upon this upper bar or erasing-plate 1 support the attachment, which comprises a frame consisting of a base-plate 5, screwed to the erasing-plate and having upwardly-extending sides or standards 6 connected therewith. These standards at their upper ends have bearings or sockets 7 to receive the journals of a supply-roll 8, consisting of a strip of the tags in the form of a roll. From this roll the strip of tags passes downwardly between a pair of feed-rolls 9 10. One of these rolls 9 is journaled in fixed bearings in the standard 6, and the other roll has its bearings in arms 11, extending from a shaft 12, journaled in the standards 6 and under tension of a spring 13, tending to force the roll 10 into feeding contact with the roll 9. The roll 9 has a detent-wheel 14, acted on by a detent 15, which arrests the feed-roll at intervals, so that the tag-strip will be advanced the space of one tag at each operation. The action of the detent 15 and the wheel 14 is substantially the same as that employed on type-writers generally and is for the purpose of accurately determining the distance between the lines when the feed-roll is moved by its operating mechanism, one line being printed on each tag. Ratchets and detents similar in effect to these are well known on the Hammond machine.

The feed-roll 9 is operated by a gear-wheel 16, loose thereon, carrying a pawl 17, engaging a ratchet-wheel 18, fixed to the roll-shaft, the said gear-wheel 16 being operated through a rack-bar 19, sliding in a guideway 20 of the base-plate 5 and having a roller 21 arranged to ride upon a cam-track 22 when the carriage is pushed from left to right for beginning a new line. This cam-track is arranged in fixed relation to the printing mechanism and is supported upon a standard 23, which in turn is supported upon the fixed cover-plate 24.

at the rear of the machine. When the type-writer carriage as a whole is returned from left to right for beginning a new line, the roller 21, riding upon the cam 22, will through the connections described operate the feed-roll 9, and thus feed down the tag-strip a distance equal to the width of one tag, and in order to accurately guide the tag-strip to the printing-point I use guide-plates 25, held by their arms 26, which are secured to the base-plate 5 of the attachment, the said guide-plates reaching down to near the upper edge of the shuttle, (indicated generally at 27,) so that the tag will lie between the said shuttle and the hammer, (indicated generally at 28.) The guide-plates 25 are shown partly in dotted lines in Fig. 1, extending down from a point immediately below the rolls 9 and 10 to a point just above the plane of the shuttle and hammer. After the feeding action has taken place the printing may be proceeded with as in ordinary practice, and after the tag is printed the balance of the movement of the carriage toward the left may be utilized for automatically severing the printed tag from the tag-strip. For this purpose I employ a cutting-knife 29, which is supported upon the frame adjacent one of the ribbon-spools, as at 30, Fig. 1, the piece of which the knife is formed extending under the ribbon-spool, then upwardly, as at 31, and rearwardly, its rear edge being sharpened to provide the cutting edge, as at 32. This cutting edge lies in a plane just above the plane of the shuttle and across the path of the tag-strip as it is carried toward the left by the movement of the carriage.

After the tag is printed it is simply necessary to release the carriage from its escapement mechanism and allow it to move freely toward the left under the action of its spring, which will bring the tag against the knife and cause it to be sheared off by the action of the same. As will be seen in Fig. 1, the knife is located just below the horizontal plane along which the lower edges of guide-plates 25 move, so that the shearing action of the knife takes place close against the lower edges of these plates.

In order to release the carriage after the printing has been done for the cutting-off action, I prefer to employ a releasing-lever the key of which is indicated at 33. The lever is pivoted at 34, and its rear end extends beneath one end of a lever 35, which is pivoted at 36 to a suitable standard and with its other end overlies the releasing-sleeve 37 of the escapement mechanism, which sleeve in its action and arrangement is the same as that well known in the Hammond type-writer and needs no particular description herein further than to say that when this sleeve is moved toward the rear it causes the release of the carriage from the escapement mechanism and places the said

carriage entirely under the influence of the carriage-spring so that it will move forcibly toward the left.

In order to cause the lever 35 to operate the release-sleeve, said lever is formed with an incline at its end to engage a part of the release-sleeve and have a camming action thereon. The lever 35 is returned to normal position by the spring 38.

It will be noticed that the attachment is 75 much shorter than the length of the carriage, and thus there is considerable movement to the carriage after the line of printing has been placed upon the tag, and this excessive movement of the carriage is utilized for the cutting 80 off of the printed tag.

The machine as above described is adapted to print upon the lower edge of the tag; but in some cases it may be desired to place additional lines of printing upon the tag, and I have therefore provided means whereby the tag-strip may be fed downwardly, so that the first line printed will be near the top thereof, and then the tag-strip may be fed upwardly, so that the whole surface of the tag may be covered by printing, as desired, and then this may be severed from the tag-strip, and the said strip will then be fed downwardly an amount sufficient to bring the next tag with its upper portion opposite the printing-point, so that by then feeding this tag upwardly step by step its whole surface may be printed upon. For this purpose the feeding action of the rolls 9 and 10 is made to exceed that described above, so that the tag will be fed downwardly until its upper portion is opposite the printing-point, and then by operating a finger-lever, such as is shown in Fig. 5 at 40, the tag-strip may be raised step by step. This finger-lever is associated with a pawl 41 and a ratchet 42, well known on the Hammond type-writer, and acting in a manner similar to that on existing machines, to feed the paper upwardly step by step. The detent-ratchet 14, with the detent 15, is arranged similarly to that above described, the only difference being that the detent-wheel has a larger number of notches therein for a smaller spacing action of the feed-rolls in feeding the tag-strip upwardly. This detent-ratchet 14' and its detent 15 are brought into use to determine accurately the positions of the tag-strip when moved upwardly by hand by means of the finger-lever, and the action of this detent mechanism is substantially the same in all respects to that occurring on the ordinary Hammond type-writer when the feed-rolls are operated by the finger-lever at the left-hand end of the carriage, the detent-rolls and detent on the ordinary machine being located on the right-hand end of the carriage. In the present case when the tag-strip is moved downwardly by means of the automatic mechanism the detent 15 will allow 125

the detent-wheel 14' to turn sufficiently for this automatic action, the said detent riding over the teeth until the full automatic action is completed, and then it performs its function of accurately positioning the feed-roll, and after this the finger-lever may be operated to raise the tag-strip up step by step, so that the whole surface thereof may be covered.

10 The detent 15 and the detent ratchet-wheel are shown in Fig. 6, and, as above indicated, the function of this detent is to hold the feed-rolls accurately in position when moved either by the automatic mechanism 15 or the hand-operating mechanism of Fig. 5, its function being the same as that in the ordinary Hammond type-writer, in that it aids in positioning the rolls accurately when moved, by preventing overthrow or any 20 tendency toward backward movement.

The finger-wheel 41' (shown in Fig. 3) for operating the feed-rolls by hand may in my improved arrangement (shown in Fig. 5) be placed at the opposite end of the feed-roll 9 25 to that upon which the finger-lever is located.

The action of the knife in this form of the invention is precisely the same as that above described, the upward feeding action of the 30 finger-lever 40 bringing the part of the tag-strip to be severed into the plane of the knife at the same time that it brings the lower portion of the said tag-strip into the printing-plane.

35 I may make the cam 22 adjustable, so as to get different degrees of movement of the rack-bar 19 for imparting different amounts of feed to the tag-strip, and for this purpose the standard 23 may be adjustably held to 40 the cover-plate 24, so that by loosening the nut 43 the standard 23 may be turned and set in different positions, and a spring-pin 44, engaging recesses in the cover-plate 24, may determine the accurate adjustment of 45 the standard 23 for different amounts of feed.

When the machine is built particularly for use in printing and cutting tags, I prefer to employ a plate 45, set in inclined position in the carriage, so as to direct the cut tags toward the rear. Instead of this, however, I 50 may employ a guide 46 to receive the tags after leaving the knife, one tag being pushed out from said guideway as another tag enters it. This guideway is screwed to the knife-bar at 47.

55 In order to cushion the movement of the carriage, I provide a dash-pot or buffer device consisting of a cylinder 48, supported on the carriage and having a piston 49 therein 60 borne upon by a spring 50, the said piston-rod extending from the head of the cylinder and arranged to strike upon a stop 51 on the frame of the machine.

I prefer to employ a tag-strip which is

scored, so that the tags may be readily severed by the action of the knife. These tag-strips are of known form and are provided with a series of perforations, one for each tag, so that when the tags are printed and severed they may be placed upon a suitable 65 hook or holding device by means of the perforations.

As regards the shuttle and hammer in their relation to each other and to the carriage, reference is made to the well-known 75 Hammond machine, such as illustrated in Patent No. 290,419, dated December 18, 1883.

It will be understood by reference to Figs. 2 and 3 that the knife 29 is located to one side of the printing-point, and the tag is of 80 such a length that it may receive the printing throughout its width before its left-hand edge reaches the severing-knife. This will be clear by reference to Fig. 2, wherein the rolls 9 and 10 are shown of a length approximately equal to the width of the tag. After 85 the tag has passed the printing-point and it has received the printing, the carriage, together with the rolls 9 and 10, will move toward the left, Fig. 2, and as the knife operates close to the lower edges of the guide- 90 plates 25 the said knife will shear off the tag which has just been printed from the strip.

I claim—

1. In combination in a type-writer, printing mechanism, means for feeding a strip of the material vertically to the printing mechanism and means for automatically severing the printed portions of the said strip from the main portion, said means comprising a knife 95 and a paper-carriage which in its longitudinal movement carries the paper against the knife, substantially as described.

2. In combination in a type-writer, printing mechanism, a carriage, feed mechanism 100 for feeding a strip of material to the printing-point and a cutting-knife arranged to sever the said material, the said carriage in its movement, carrying the strip of material against the knife to be severed thereby. 105

3. In combination in a type-writer, printing mechanism, means for feeding a strip of material to the printing mechanism, a carriage carrying the said feed means, a knife and releasing means for the carriage to allow 110 the same under the impulse of its spring to carry the strip against the knife to be severed thereby, substantially as described.

4. In combination, in a type-writer with printing mechanism, a carriage, feed means 115 thereon for feeding a sheet or strip of paper to the printing mechanism, a knife for severing the sheet or strip when moved across the same by the action of the carriage, and a releasing-key for releasing the escapement 120 mechanism to cause the carriage to move the paper against the knife, substantially as described.

5. In combination with printing mechanism, a carriage, feed mechanism, a cutting-knife, escape mechanism for the carriage including the releasing-sleeve and a key-lever with means for causing the release of the sleeve, whereby the paper-carriage carries the paper against the knife, substantially as described.

6. In combination, printing mechanism, a carriage, feed-rolls, a rack moving transversely of the carriage, connections between the rack and the feed-rolls for operating the same and a cam or track fixed on the frame for operating the rack, substantially as described.

7. In combination, in a type-writer, printing mechanism comprising a hammer and a shuttle, feed-rolls, means for operating the same to feed the paper downwardly and in a vertical plane between the shuttle and the hammer, said means operating automatically by the movement of the carriage, and manually-operated means for feeding the paper

upwardly between said hammer and shuttle, substantially as described.

8. In combination, printing mechanism, a carriage having feed-rolls, automatically-operating means for feeding the paper downwardly, manually-operating means for feeding the paper or strip upwardly, and means for severing the said paper strip, substantially as described.

9. In combination, printing mechanism, a carriage, guides for directing the paper to the printing-point, feed-rolls, and a knife co-operating with the guides to shear the paper, said carriage on its movement carrying the paper against the knife, substantially as described.

In testimony whereof I affix my signature in presence of two witnesses.

JOHN ANDERSON RUFFIN.
